UNITED STATES PATENT OFFICE.

CHARLES R. MURRAY, OF SAN FRANCISCO, CALIFORNIA.

METHOD AND APPARATUS FOR EXTINGUISHING FIRES.

Application filed November 9, 1922. Serial No. 589,752.

This invention relates to a method of and apparatus for extinguishing fires, and more particularly fires occurring in large oil tanks.

5 So far as I am aware, it has not heretofore been proposed to use water in fighting fires occurring in large storage tanks where oil is present. The usual method of extinguishing such fires is to employ a chemical 10 which is lighter than oil, so that by floating it on the surface the flames are smothered out. The apparatus required for this purpose is extremely expensive, and the difficulty of separating the chemical from the 15 oil after the fire is extinguished offers another objection.

The object of the present invention is to extinguish fires, and particularly oil tank fires, in an economical and rapid manner 20 and without the use of chemicals which are liable to become so mixed with the oil as to make it difficult to separate and salvage the oil. This object I accomplish by the use of a sheet or curtain of water to completely 25 surround the fire and cut off the supply of oxygen thereto, and simultaneously directing a number of jets of water directly on to the source of the fire.

One form of apparatus suitable for practicing my invention is shown in the accompanying drawing, wherein—

Fig. 1 shows a plan view of a tank equipped with apparatus embodying my invention.

35 Fig. 2 shows a side elevation, partly in section, of the tank and apparatus shown in Fig. 1.

Fig. 3 shows a sectional view of one of the nozzles or distributors employed in connection with the apparatus.

In carrying out my invention I make use of a nozzle or distributor, such as shown in Fig. 3, which comprises a casing 10 screw-threaded at one end for coupling on to a supply pipe 11. The outlet end of the nozzle is tapered, as shown at 12, and inside the nozzle or casing is a spider 13 on to which is screw-threaded a hollow stem 14 carrying at its outer end a distributing disk 15. This disk causes the water to be thrown out laterally in a disk-like or conical sheet or stream, as indicated by the arrows 16. Also the disk is perforated at its center to permit water from the hollow stem to pass out in jets, as shown by the arrows 17.

In practice, where it is desired to protect

a large storage tank a number of these nozzles are arranged at the top of a tank or enclosure 18 and connected with supply mains 19. The lateral spread or stream from the nozzles is shown in dotted lines in Fig. 1. Sufficient of these nozzles are used so that the combined lateral spread or streams will completely fill the cross sectional area of the tank or enclosure.

When a fire occurs all the nozzles are turned on simultaneously, either by hand or by any suitable automatic mechanism. The streams from the nozzles completely seal off the lower portion of the tank, so that air cannot gain entrance to the source of the fire. At the same time, the downwardly directed jets from the tip of the distributing disks will act directly upon the fire and assist in extinguishing the same. Furthermore, the lateral streams striking the sides of the tank will assist in cooling the same and prevent rupturing of the tank through expansion.

It will be understood that various changes in the arrangement and construction of the several parts herein shown and described may be employed without departing from the spirit of my invention as disclosed in the appended claims.

Having thus described my invention, what I claim and desire to secure by Letters Patent is:

1. A method of extinguishing fires in tanks and enclosures containing inflammable liquids, which consists of projecting from different points in the confines of the enclosure horizontally directed, discoidal sheets of liquid, under high pressure and sufficiently widespread and closely spaced to cover without interruption the entire cross-sectional area of the enclosure above the surface of the inflammable liquid and below the top of the enclosure, whereby the heat of the flame will be cut-off from the surface of the burning liquid and further generation of combustible vapors retarded.

2. The method of extinguishing fires in tanks and enclosures containing inflammable liquids, which consists in projecting from different points between the center and periphery of the tank, a plurality of high velocity, discoidal sheets of water, over and above the surface of the inflammable liquid and below the top of the enclosure, and causing the water curtains to strike each other and the sides of the enclosure so

as to produce a relatively thick, horizontal zone of water and mist, capable of cooling the surface of the burning liquid and cutting off the transmission of heat thereto by 5 the upper portion of the flame, so as to retard generation of combustible vapors.

3. An apparatus for extinguishing fires in tanks and similar enclosures containing inflammables, comprising a plurality of vertically disposed nozzles spaced laterally 10 from each other between the center and pe-

riphery of the tank, and arranged above the surface of the inflammable substance, and a distributing disc disposed in front of each nozzle to spread the liquid in horizontal, 15 discoidal sheets, and means for supplying liquid to said nozzles under relatively high pressure, so that horizontally directed, discoidal sheets of liquid may be projected without interruption throughout the entire 20 cross-sectional area of the tank.

CHARLES R. MURRAY.
